Fig. 2

Inventor:
Edgar W. Gent,
by W. E. Bestby, Atty.

UNITED STATES PATENT OFFICE.

EDGAR W. GENT, OF MORRISTOWN, NEW JERSEY, ASSIGNOR TO WESTERN ELECTRIC COMPANY, INCORPORATED, OF NEW YORK, N. Y., A CORPORATION OF NEW YORK.

RATCHET MECHANISM.

Application filed August 31, 1921. Serial No. 497,126.

To all whom it may concern:

Be it known that I, EDGAR W. GENT, a citizen of the United States, residing at Morristown, in the county of Morris, State 5 of New Jersey, have invented certain new and useful Improvements in Ratchet Mechanisms, of which the following is a full, clear, concise, and exact description.

This invention relates to ratchet mechanisms.

An object of the invention is to provide a ratchet of the relatively noiseless type with means for preventing its overthrow.

A feature of the invention consists in the combination with a driven ratchet member of a driving pawl, means cooperating with the ratchet member for positively moving the pawl into position to operatively engage the ratchet member during the forward movement of the pawl and means for preventing overthrow of the ratchet. This means, in its preferred form, comprises a lug integral with the driving pawl which is arranged to engage a fixed stop for moving 25 the cam end of the pawl into the path of the teeth of the ratchet member.

Figs. 1 and 2 of the drawing show the preferred form of the invention in different operating positions.

The ratchet wheel 1, as shown, is provided with six teeth, 1^1 , 1^2 , 1^3 , 1^4 , 1^5 , 1^6 , and is secured to the spindle 2 and rotatable therewith. The member 3 is preferably journaled on spindle 2 about which it is rotatable, and may, for example be attached to or form a part of the finger wheel of an automatic telephone calling device, such as that shown in U. S. Patent No. 1,161,854, issued to O. F. Forsberg November 30, 1915. The members 4 and 5 are each pivoted on member 3 by means of pins 6 and 7, respectively and comprise an arm 8 which operates as a pawl and a cam arm 9 which cooperates with the teeth of the ratchet to control its associated pawl 8. As illustrated, each pivoted member 4 and 5 subtends two ratchet teeth.

In Fig. 1, the member 3, together with the members 4 and 5 are indicated by an arrow as moving in a clockwise direction during which movement, as is evident, the ratchet wheel 1 remains stationary. The end of the pawl 8 of the member 4 is situated midway between the teeth 1^1 and 1^2 , whereas the end of the pawl 8 of the member

5 is disposed at the top of the tooth 1^4 . The 55 end of the arm 9 of the member 4, which is suitably curved, is seen to be engaged with the tooth 1^3 and it is evident that in this position the end of the pawl 8 of the same member is in position to engage tooth 1^1 upon 60 a movement in the direction indicated in Fig. 2, in which figure said pawl is seen to have engaged the tooth 1^1 .

Now with reference to Fig. 1, let it be assumed that the member 3 is turned through 65 a considerable angle so that the pivoted members 4 and 5 pass over several ratchet teeth. It is apparent from the drawing that each time the end of an arm 9 engages a ratchet tooth, the end of the pawl 8 associated therewith will be moved toward the spindle 2, and accordingly into position to engage one of the ratchet teeth. It is also apparent that the end of the pawl 8 in passing each ratchet tooth, moving in the direction indicated in Fig. 1, will be moved out of engageable relation to the ratchet teeth. The pawl 8 of the member 5 in Fig. 1 illustrates this last-mentioned condition. It will be seen that said pawl, after passing the 70 tooth 1^4 , will remain out of the path thereof until the end of the arm 9, associated with said pawl, is moved outwardly by the action of tooth 1^6 .

While the mechanism described comprises 85 two pawls, it is not at all essential to the operation of the invention that more than one pawl be employed. The reason for using two or more pawls properly distributed with respect to the ratchet teeth is to reduce the 90 maximum distance which the member 3 would have to turn in the direction indicated in Fig. 2 before one of the pawls engages the tooth. Such arrangement is common in ordinary ratchet mechanisms, and does not 95 constitute a part of the present invention.

Where it is desirable to stop the ratchet wheel immediately after the driving member comes to rest, a fixed stop 10 may be provided to engage the lug 11 which is preferably integral with one of the pivoted members, such as 4, upon which engagement the member 4 is rotated to press the curved end or cam portion of the arm 9 against the ratchet wheel, or preferably, against the back 100 of one of the ratchet teeth. This action immediately brings the ratchet 1 to rest.

In the appended claims, the curved end

of the arm 9, which engages the ratchet teeth, is referred to as a cam or a cam portion.

What is claimed is:

5. 1. In combination, a toothed ratchet, a member comprising a pawl and a cam for cooperating with said ratchet and a stop for engaging said member to throw said cam into engagement with said ratchet to prevent overthrow thereof.
- 10 2. In combination, a ratchet, a bifurcated pivoted member, one arm of which is a driving pawl for said ratchet, and a stop op-

erable to engage and rotate said pivoted member to move the other arm thereof into engagement with said ratchet to prevent overthrow of said ratchet.

- 15 3. In combination, a toothed ratchet member, a driving pawl for said ratchet member, a fixed stop for limiting the movement of said pawl and braking means operable by said stop to engage said ratchet member.

In witness whereof, I hereunto subscribe my name this 23rd day of August A. D., 1921

EDGAR W. GENT.
